UNITED STATES PATENT OFFICE.

FRANCIS A. WALSH, OF MILWAUKEE, WISCONSIN.

SHEET-METAL VESSEL.

SPECIFICATION forming part of Letters Patent No. 421,335, dated February 11, 1890.

Application filed October 22, 1888. Serial No. 288,798. (No model.)

To all whom it may concern:

Be it known that I, FRANCIS A. WALSH, of Milwaukee, in the county of Milwaukee, and in the State of Wisconsin, have invented cer-
5 tain new and useful Improvements in Sheet-
Metal Vessels; and I do hereby declare that
the following is a full, clear, and exact descrip-
tion thereof.

My invention relates to sheet-metal vessels;
10 and it consists in certain peculiarities of con-
struction, as will be fully set forth hereinafter.

In the drawings, Figure 1 is a sectional view
of my present invention, showing a slip-cover
in connection therewith; and Fig. 2 is a side
15 elevation of the same without the slip-cover,
and broken away at one point to show the con-
struction.

A is the can-body, formed of one or more
20 pieces of sheet metal bent so as to be circular
in cross-section, and having its upper edge
formed with a continuous internally-rolled
rim, free from wire or other extraneous in-
25 ternal support, such as is shown and claimed
in my application for patent filed August 1,
1887, and which is here marked a. Below
this the can-body is creased or crimped in-
ward, as shown at b, forming an internal
30 bead, to which is secured the inturned round-
ed edge c of a cover C, and over all I put a
slip-cover D, whose downturned edge d cov-
ers the point of union of the parts b and c.

I may either form the crease b in the can-
body before the cover C is secured thereto
and afterward crimp the latter to place there-
35 on, or I may in the first place leave the can-
body straight at this point, slip the cover C

(with its downturned edge c then straight
also) to place, and crimp both the can-body
and cover together at one operation to the
shape shown in Fig. 1, at b c, as preferred. 40

The cover C is not intended to be perma-
nently sealed or soldered to the can-body, but
is held tightly in place as long as wanted,
after which it can be readily pried off, and then,
if preferred, the slip-cover D may alone be 45
used.

While I have shown a vertically-sided ves-
sel, a slip-cover with a horizontal top, and an
inner cover also with a horizontal top, but at
a plane lower than its rounded rim or edge, 50
these are unimportant details, and may be
varied in any way desired to suit the taste or
requirement of the customer without depart-
ing from the spirit of my invention.

Having thus described my invention, what 55
I claim as new, and desire to secure by Letters
Patent, is—

In a sheet-metal vessel, the combination of
the body A, having an internally-rolled upper
rim a and an inward crease or crimp b just 60
below the same, with a cover C, having a
rounded inturned downward edge c, crimped
or held against the parts a b, just described,
substantially as set forth.

In testimony that I claim the foregoing I 65
have hereunto set my hand, at Milwaukee, in
the county of Milwaukee and State of Wis-
consin, in the presence of two witnesses.

FRANCIS A. WALSH.
